UNITED STATES PATENT OFFICE.

PAUL SCRIVE, OF PARIS, FRANCE.

ROTARY DRYING APPARATUS.

Application filed January 12, 1924. Serial No. 685,855.

To all whom it may concern:

Be it known that I, PAUL SCRIVE, a citizen of the French Republic, residing 1 Rue de la Reale, Paris, France, have invented 5 new and useful Improvements in Rotary Drying Apparatus, of which the following is the specification.

Rotary drying apparatus with inclined axes are already known, having side walls 10 in the shape of buckets and longitudinal openings between two adjacent buckets for the admission of the hot gases which are sucked by the axis of the drum, which axis is hollow and perforated with 15 radial holes. These drying apparatus are so constructed that the materials contained in a bucket are discharged, during the rotation of the drum, into the following buckets; but it very frequently happens that the 20 materials treated stick to the walls and that they come off at a time their fall carries them outside the drum through the longitudinal openings of the latter.

This inconvenience would be rendered 25 still more serious in case it should be desired to introduce the hot gases in the drum through the hollow perforated axis, these gases being evacuated through the longitudinal openings. In fact, in this case, it is 30 obvious that the gases, by escaping through the side openings of the drum, would still facilitate the issue of a portion of the materials from the drum.

The improvement forming the subject-matter of the present invention is adapted 35 to do away with this inconvenience and to thus permit, if desired, the introduction of hot gases under pressure through the central hollow shaft.

40 The accompanying drawing illustrates, by way of example only, a form of carrying out this invention.

Fig. 1 is a cross-section of the drum.

Fig. 2 is a partial sectional elevation.

45 In this example, the drying drum is essentially constituted by groups of longitudinally arranged sheet-iron plates 1 and 2; in each group 1-2, the sheet-iron plates have a common edge, at 3, so as to form, in cross section, a more or less open V. The edges 3 are so arranged as to constitute the edges of a regular prismatic surface, a hexagonal surface 50 in the example illustrated. The improvement forming the subject-matter of the invention consists in arranging on the inner 55 face of the walls 2, and at their end 4, a

sheet-iron plate 5 which connects them to the walls 1. The sheet-iron plates 5 are perforated with holes of small diameter. These perforations are provided only on the 60 zone 6-7, that is to say preferably on about half the width of the sheet-iron plates. Another sheet iron plate 8 is provided, the edge 9 of which is in the plane joining the 65 edge 3 to the line 7.

The admission of the materials takes place through the spout 10; a fixed obturating plate 11 is rigid with this spout and the shaft 12 passes through this plate 11. On the other hand, the drum carries at its end 70 an annular closing sheet iron plate 13, the edges of which slightly extend beyond those of the circular fixed plate 11. In this manner, the materials cannot escape through the 75 end of the drum.

The hot gases enter the drum thus constituted through openings which exist between the edge 4 and the adjacent sheet-iron plate 1, the hot gases being first in contact with the most moist materials, near the charging 80 end of the rotating drum.

The materials received in each of the V's constituted by the sheet-iron plates 1-2 are progressively distributed, owing to the rotation of the drum in the direction of the arrow f', on the sheet-iron plate 1. When the wall under consideration passes beyond the horizontal, the materials to be dried flow over the edge of the sheet-iron plate 1 and fall into the following V which is presented 90 at this moment under the said sheet-iron plate. During the fall of the material the latter forms a screen through which pass the hot gases. Besides, as the overflowing continues during a certain angular displacement 95 of the drum, it follows therefrom that the materials which originally were the nearest the overflowing edge are, when reaching the following sheet-iron plate, the farthest from the overflowing edge limiting the latter. Consequently, at each stage of overflowing, the materials which were the less ventilated, 100 are, on the contrary, subjected to the most considerable ventilation, action of displacement to which is added that resulting from the fall of the materials in the stream of hot gases. All these arrangements are already 105 known.

But, it happens that agglutinated materials stick to the bottom of the V formed by 110 the sheet-iron plates 1 and 2; when these materials come off once the V has passed the

vertical, the materials which are not stopped by the sheet iron plate 8 can fall on the sheet iron plate 5 only in the non-perforated zone 7-4 and fall again in the V when the latter arrives to its lower position. In the same way, the materials collected by the sheet iron plate 8 also fall again at this moment in the V.

In the example illustrated, use is made 10 of sheet-iron plates 14, preferably plane, so that the materials which remain attached to the projecting parts 15 fall back upon these plates according to the path indicated by the surfaces covered with dotted lines. 15 The sheet-iron plates 14 overlap each other, thus forming a second inner polygonal casing, letting the hot gases pass through the intervals 16 which separate them, but preventing the fall of the materials on the hollow 20 shaft, thus avoiding the obturation of the radial holes. The sheet-iron plates 14, licked by the hot gases, have, moreover, for effect to increase the useful surface of the apparatus and, consequently, its efficiency 25 and capacity of utilization.

Of course, the projecting parts 15 can be provided in any number and the various sheet-iron plates can have any shape. It will also be understood that the multiplicity 30 of the screens of materials freely falling down, screens through which pass the hot gases, ensures a better utilization of these gases, the passage of which in the apparatus lasts a longer time owing to a more sinuous 35 path.

What I claim as my invention and desire to secure by Letters Patent is:

1. In a rotary drying apparatus having an inclined axis for pulverulent materials, 40 a drum constituted by the assemblage of several longitudinal buckets, the concavities of which are turned inwardly, the said buckets being arranged in a geometrically

similar manner relatively to the axis of the drum, and providing between them equal intervals, longitudinal plates obturating the said intervals, these plates being perforated on a portion of their width. 45

2. In a rotary drying apparatus having an inclined axis for pulverulent materials, 50 a drum constituted by the assemblage of several longitudinal buckets, the concavities of which are turned inwardly, the said buckets being arranged in a geometrically similar manner relatively to the axis of the drum, and providing between them equal intervals, longitudinal plates obturating the said intervals these plates being perforated on a portion of their width, other plates arranged for protecting these perforated portions. 55

3. In a rotary drying apparatus having an inclined axis for pulverulent materials, 60 a drum constituted by the assemblage of several longitudinal buckets, the concavities of which are turned inwardly, the said buckets being arranged in a geometrically similar manner relatively to the axis of the drum, and providing between them equal intervals, buckets each constituted by two 65 sheet-iron plates forming a dihedral angle, the arrangement of these buckets so that the apex of each dihedral angle coincides with the edge of a prismatic surface having for straight section a regular polygon, longitudinal plates obturating the intervals provided between the buckets, these plates being perforated on a portion of their width, other plates arranged for protecting the perforated portions, and extending up to a plane 70 connecting the apex of the dihedral angle to the limit of the perforated portion. 75

In testimony whereof I have signed my name to this specification.

PAUL SCRIVE.
